UNITED STATES PATENT OFFICE.

RUBIN ROSENTHAL, OF NEW YORK, N. Y.

RING-SETTING.

1,081,153.

Specification of Letters Patent.

Patented Dec. 9, 1913.

Application filed March 14, 1913. Serial No. 754,218.

To all whom it may concern:

Be it known that I, RUBIN ROSENTHAL, a citizen of the United States, and a resident of the city of New York, borough of 5 Manhattan, in the county and State of New York, have invented a new and Improved Ring-Setting, of which the following is a full, clear, and exact description.

This invention relates to improvements 10 in ring setting and has for an object to provide an improved structure for producing the same finish from the top of the setting downwardly through the ring.

Another object of the invention is to provide a setting with an extending sleeve designed to project through the ring so as to provide an anchoring device and a reflecting device of the same kind as the fingers or prongs of the setting.

20 A still further object of the invention is to provide a setting formed of a sheet or layer of gold or other metal, and an inner layer of a different metal, as for instance platinum, the setting being formed with a 25 projecting sleeve designed to extend through the ring, whereby the inner layer of platinum will be exposed for the full depth of the setting, and the thickness of the ring in order to properly reflect light upon a 30 stone carried by the prongs of the setting.

In carrying out the objects of the invention, a ring of any desired kind is taken and formed with a hole or aperture there-through preferably at the thickened portion 35 thereof, also the ring is preferably formed with shouldered or thickened portion surrounding the hole so as to receive a setting having a shouldered or thickened portion, and having a shank or tubular 40 member extending through the hole or aperture in the ring. This provides a strong rigid structure and also allows of the use of a reflecting material, as for instance platinum, which will extend from the top of 45 the setting entirely through the ring and thus provide a proper reflecting medium for the stone carried by the prongs of the setting.

A practical embodiment of the invention 50 is represented in the accompanying drawings forming a part of this specification in which similar characters of reference indicate corresponding parts in all the views.

Figure 1 is a side view of a ring, the upper part being shown in section for better disclosing the invention; and Fig. 2 is a

view similar to Fig. 1, but showing a slightly modified structure. Fig. 3 is a side view of a stone mount or setting.

Referring to the accompanying drawings 60 by numerals, 1 indicates a ring of any kind, as for instance a gold ring, provided with an enlargement 2 in which an aperture 3 is formed. A shouldered portion 4 is also provided for engaging a shouldered portion 5 of the setting 6. The setting 6 is provided with an annular tubular member or extension 7, extending through aperture 3 and forming a lining therefor. The setting 6 is formed with any desired number of prongs 70 8 for receiving and holding a stone of any kind. It will be observed from Fig. 1 that the same colored metal will be disclosed from the upper or outer point of the prongs 8 to the bottom of the tubular member 7. 75 When the setting 6 is made of platinum and the interior is burnished, a reflecting background is provided for the stone for causing the same to reflect light in a better manner.

80 In Fig. 2 a slightly modified form of the invention is shown in which the setting 6' is provided with a lining 9 of platinum, the outer part of the setting being gold or any other desired material, preferably of the 85 same kind of material as the ring 1'. By providing the lining 9, the same effect is produced in respect to the reflection of the light as is produced in the form shown in Fig. 1, and in addition the outer part of the 90 setting is caused to resemble the material of which the ring 1' is made, as for instance gold. In this way there will be no contrast between the outer appearance of the setting and the ring, but the full reflecting effect of 95 the burnished platinum will be provided.

In carrying out my invention it will be noticed that I secure by the construction presented a setting in which the body of the setting is of sufficient thickness to secure the 100 strength desired, the bore is uninterrupted from end to end of the setting, the thickness of the tapered cylindrical extension is reduced and the downwardly facing shoulder aids in securing the desired strength at the 105 union between the ring and the setting when applied thereto and also secures the union in such manner as to aid in effecting a coincidence and merger between the lines of the outer side of the body of the setting and the 110 meeting lines on the outer surface of the ring to which the setting is applied, thus

contributing to the effect in the set ring commonly recognized as the "Tiffany setting."

Having thus described my invention, I claim as new and desire to secure by Letters

5 Patent:—

1. A ring setting comprising a body portion formed with retaining prongs, and a tapering tubular extension at the base of the body portion, an integral external downwardly facing shoulder being formed at the juncture of the body and extension and aiding in securing a coincidence and merger between the lines of the outer side of the body of the setting and those of the ring to which
- 10 the setting is applied, the wall of the extension being of less thickness than that of the body portion, and the setting having a bore extending from end to end through the body portion and extension and tapering
- 15 toward its inner end on an uninterrupted line, all substantially as described, whereby the thickness and strength is secured in the body of the setting, the uninterrupted bore is unaffected and the desired strength of connection with a ring is aided by the shouldered construction of the setting, substantially as set forth.
- 20 2. In a setting of the class described, the combination with a ring having a shouldered portion in which is arranged a taper-
- 25
- 30

ing aperture, said shouldered portion having a flat annular upper face, of a setting comprising a body portion formed with retaining prongs, and a tapering tubular extension at the base of the body portion, an integral external downwardly facing shoulder being formed at the juncture of the body and extension and aiding in securing a coincidence and merger between the lines of the outer side of the body of the setting and those of the ring to which the setting is applied, the wall of the extension being of less thickness than that of the body portion, and the setting having a bore extending from end to end through the body portion and extension and tapering toward its inner end on an uninterrupted line, all substantially as described, whereby the thickness and strength is secured in the body of the setting, the uninterrupted bore is unaffected and the desired strength of connection with a ring is aided by the shouldered construction of the setting, substantially as set forth.

In testimony whereof I have signed my name to this specification in the presence of two subscribing witnesses.

RUBIN ROSENTHAL.
